UNITED STATES PATENT OFFICE.

JESSE LAIRD McGARITY, OF ATLANTA, GEORGIA.

DESIGN FOR HOSE.

Application filed April 14, 1926. Serial No. 17,293. Term of patent 14 years.

To all whom it may concern:

Be it known that I, JESSE L. McGARITY, a citizen of the United States, and a resident of Atlanta, in the county of Fulton and State of Georgia, have invented a new, original, and ornamental Design for Hose, of which the following is a specification, reference being had to the accompanying drawing, forming part thereof.

I claim:

The ornamental design for hose, as shown.

JESSE LAIRD McGARITY.
